(57) CLAIM

The ornamental design for the men's shoe with gem as shown and described.

DESCRIPTION

FIG. 1 is a perspective view of a men's shoe with gem; FIG. 2 is a left side elevational view thereof;

FIG. 3 is a right side elevational view thereof;

FIG. 4 is a top plan view thereof;

FIG. 5 is a bottom plan view thereof;

FIG. 6 is a front side elevational view thereof; and,

FIG. 7 is a back side elevational view thereof. The evenly spaced broken lines in FIGS. 1-7 represent portions of the men's shoe with gem that form no part of the claimed design.

1 Claim, 4 Drawing Sheets
